COMBINED STIRRING AND SCRAPING SPOON

Robert E. Scigliano, 176 Vinal St.,
Revere, Mass. 02151

Filed Dec. 17, 1974, Ser. No. 533,635

Term of patent 14 years

Int. Cl. D7—03

U.S. Cl. D7—148

FIG. 1 is a front elevational view of a combined stirring and scraping spoon showing my new design;

FIG. 2 is a rear elevational view thereof; and
FIG. 3 is a side elevational view thereof.

I claim:

The ornamental design for a combined stirring and scraping spoon, as shown and described.
